[57] **CLAIM**

The ornamental design for sash lock, as shown and described.

DESCRIPTION

FIG. 1 is a top, front, and left side perspective view of a sash lock showing our new design, the broken-line disclosure of a portion of a window being for illustrative purposes only and forming no part of the claimed design;

FIG. 2 is an enlarged top, front, and left side view thereof;

FIG. 3 is an enlarged top, front, and left side perspective view of the keeper portion thereof;

FIG. 4 is an enlarged top, front, and left side perspective view of the latch portion thereof;

FIG. 5 is an enlarged top plan view of the keeper portion thereof;

FIG. 6 is an enlarged front elevational view of the keeper portion thereof;

FIG. 7 is an enlarged rear elevational view of the keeper portion thereof;

FIG. 8 is an enlarged left side elevational view of the keeper portion thereof, the right side being a mirror image of that shown;

FIG. 9 is an enlarged top plan view of the latch portion thereof;

FIG. 10 is an enlarged rear elevational view of the latch portion thereof;

FIG. 11 is an enlarged front elevational view of the latch portion thereof;

FIG. 12 is an enlarged left side elevational view of the latch portion thereof; and,

FIG. 13 is an enlarged right side elevational view of the latch portion thereof.
